UNITED STATES PATENT OFFICE.

SIMON B. KEFFER, OF DES MOINES, IOWA, ASSIGNOR OF ONE-HALF TO STACY JOHNS, OF SAME PLACE.

HEEL OR COUNTER SUPPORT FOR BOOTS AND SHOES.

SPECIFICATION forming part of Letters Patent No. 268,497, dated December 5, 1882.

Application filed March 16, 1882. (No model.)

To all whom it may concern:

Be it known that I, SIMON B. KEFFER, of Des Moines, in the county of Polk and State of Iowa, have invented a Counter-Support and Improved Boots and Shoes, of which the following is a specification.

The object of my invention is to facilitate and improve the construction of boots and shoes by forming and applying metal heel-stiffeners to prevent the counters from yielding to lateral pressure and allowing the feet of the wearer to assume inclined or twisted positions relative to each other, to retain the heels of boots and shoes straight, so that they will wear off evenly, and to avoid the dangers and accidents incident to wearing boots and shoes that have broken-down counters and crooked, uneven heels, and also to conceal the metal plates and stiffeners and to prevent them from chafing the heels of the wearer.

Heretofore a heel-stiffening metal plate and counter-support has been fastened against the outside of a heel in such a manner that it would extend over the counter and down under the edge of the heel to form a part of the bearing of the heel. A plate having flexible pointed tangs extending at right angles therefrom has also been fastened against the outside of a heel by driving the tangs into the heel. A steel plate having a perforated flange at its bottom and a perforation in its top has also been fixed to the inside of a counter in such a manner that its flange extended horizontally between the inner and outer soles, to be fastened by means of nails driven downward through the perforations into the heel. But a metal plate formed and applied to the outside of a boot or shoe is unsightly, liable to catch and retain dirt, and is not adapted to be fixed to the inside or between the counter and the upper or outside leather; and a metal plate fixed to the inside of a counter and having a flange extending horizontally between the inner and outer soles is liable to chafe the heel of the wearer, and is not adapted to be fixed to the outside of the counter-piece and combined with the inner sole and the upper or outside leather by means of nails while lasting the boot or shoe, as contemplated by my invention, which consists in forming an elbow-

shaped plate in such a manner that it can be nailed fast between the insole and counter and the upper or outside leather, and covered by the counter on the inside to prevent contact with and chafing of the heel of the wearer, as hereinafter fully set forth, in such a manner that it will be invisible and close to the heel of the wearer, to serve as an elbow-shaped lever in utilizing the weight and pressure of the person and foot in supporting the counter in a vertical position and maintaining the boot or shoe, and also the foot, straight, square, and flat upon the ground or floor, as required to support weak ankles and to wear off the bottoms evenly.

Figure 1 of my accompanying drawings is a top view of a blank cut from a steel plate by means of a suitable die and press or forged from a metal bar. *a* is a flat circular-shaped top end adapted to fit against the heel-counter of a boot or shoe. *b* is the lower end, of corresponding form, perforated and adapted to be fixed against the under side of the heel portion of an insole, to clamp the edges of the counter and the insole together. *c* is the connecting central portion between the flat parts *a* and *b*. It has a slot, *d*, to allow nails to be driven through, and is made thicker than the flat ends *a* and *b* to increase its strength.

Fig. 2 is a modified form of my blank *a b c d*, in which the connecting part *c* is widened, and has two slots, *d*, through which nails may be driven in fixing it to a boot or shoe.

Fig. 3 represents the blank bent and complete. In place of forming and bending wrought metal to produce my counter-supports, they may be made of malleable iron or other suitable material by casting them in molds.

Fig. 4 is a sectional view of a boot-heel, and illustrates my manner of applying my counter-support by combining it with the counter and insole and concealing it with the upper and outside portion of the leather and the complete heel. *f* represents the counter, and *g* the heel portion of an insole fixed to a last in a common way. My counter-support *a b c d* is then placed in position, as shown, in such a manner that the top portion, *a*, will extend vertically on the outside of the counter and the lower portion, *b*, horizontally inward and un-

der the counter to lap upon the insole. After being thus placed the three parts—the metal counter-support, the counter, and the insole—are fastened together by means of nails 1 2 being driven through the perforations in the metal and into the leather counter and insole and clinched fast therein. The heel part of the upper-leather is then drawn in place over the counter and metal counter-support and fastened by means of pegs or nails driven through the leather at the sides and through the slots of the metal counter-support, to firmly unite all the parts while lasting a boot or shoe.

Fig. 5 is a perspective view of a boot having a part of its heel removed to show the position

of my invisible counter-support, indicated by an outline of its form in broken lines.

I claim as my invention—

An improved metallic counter-support for boots and shoes, consisting of a metal plate 20 of the form shown and described, and provided with perforations at one end and with a longitudinal slot or slots in its central bent or curved portion, all substantially as and for the purposes stated.

SIMON B. KEFFER.
